UNITED STATES PATENT OFFICE.

FRANK WALLBERG, OF NEW YORK, N. Y.

COMBINED RECEIVER AND DETECTOR FOR WIRELESS USE.

1,219,888.

Specification of Letters Patent. Patented Mar. 20, 1917.

Application filed September 21, 1915. Serial No. 51,769.

To all whom it may concern:

Be it known that I, FRANK WALLBERG, a citizen of the United States, and a resident of the city of New York, borough of Manhattan, in the county and State of New York, have invented a new and Improved Combined Receiver and Detector for Wireless Use, of which the following is a full, clear, and exact description.

10 This invention relates to wireless systems of communication and has for its general objects to provide a telephone receiver and detector combined into a **unitary** device which is of such small size as to be conveniently carried about on one's person and which is easily and quickly connected to ground, and an aerial conductor for use in receiving wireless messages, the combined receiver and detector being held by the hand 20 to the ear.

A more specific object of the invention is the provision of a wireless receiving device which embodies a detector bridged across the terminals of the electromagnet of the 25 telephone receiver and mounted within the casing of the receiver just under the diaphragm, and associated with the receiver and mounted on the casing thereof is a rheostat in series with the telephone electromagnet and detector, so that the device can 30 be adjusted for various wave lengths.

With such objects in view, and others which will appear as the description proceeds, the invention comprises various novel 35 features of construction and arrangement of parts which will be set forth with particularity in the following description and claims appended hereto.

In the accompanying drawing which illustrates one embodiment of the invention, and wherein similar characters of reference indicate corresponding parts in all the views,

Figure 1 is a side view of the receiving device with a portion of the casing removed 45 to show the resistance wires of the rheostat;

Fig. 2 is a back view of the device;

Fig. 3 is a central vertical section;

Fig. 4 is a front view with the diaphragm-holding cap removed; and

50 Fig. 5 is a diagrammatic view of the various circuit connections.

Referring to the drawing, the device comprises a casing A composed of two concentric cylindrical shells 1 and 2, a rear plate 55 or head 3 having an annular flange 4 to which the shells are fitted, a cup-shaped

holder 5 fitting into the shells, and a cap-piece 6 which screws onto the cup or holder 5 so as to clamp between the cap 6 and holder the diaphragm 7 of the telephone transmitter. In the cup-shaped holder is the electro-magnet 8 which operates on the diaphragm 7 to emit sound vibrations through the opening 9 of the cap 6. The ends 10 and 11 of the magnet windings 12 are connected with terminal plates 13 and 14 respectively mounted on a supporting ring 15 within the holder 5. The terminal 13 is connected by a wire 16 with a binding post 17 on the rear plate 3 of the device, 76 which binding post is adapted to be connected to ground, as shown in Fig. 5. The other terminal 14 of the electro-magnet is connected by a wire 18 with a movable contact 19 of a rheostat 20, the circular row of 75 contact points 21 and the contact 19 being mounted in the rear plate 3 of the casing. One of the terminal contact points of the rheostat is connected by a wire 22 with a binding post 23 that is adapted to be connected with an aerial conductor 24 which 80 may be any metal object, structure, wire or the like suitable to answer as an antenna. The resistance windings 24 of the rheostat are coiled around the inner shell 2 of the 85 casing and are surrounded by the outer shell 1, leads 25 being taken off from the windings to the respective contact points 21. A detector 26 is shunted across the terminals 13 and 14 of the telephone electromagnet. 90 This detector comprises a suitable crystal 27 resting on a conductor plate 28 that is connected by a wire 29 with the terminal 13, and bearing on the crystal is a conductor 30 in the form of a wire which is connected with 95 the terminal 14. The plate 28 and crystal 27 are suitably supported and incased or embedded in some plastic insulating material 31, the detector being positioned to one side of the electromagnet and under or behind 100 the diaphragm 7. According to this arrangement the three essential elements of a receiving outfit, namely, the telephone receiver, the detector and variable resistance, are all mounted in a single casing so as to 105 constitute a unitary device, and to make use of the device it is merely necessary to connect the binding posts 17 and 23 by wires with the ground and some suitable part that will act as an antenna.

110 From the foregoing description taken in connection with the accompanying draw-

ing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

15. 1. A wireless receiving outfit comprising a casing and including a detector in the casing, said detector including a crystal, a conductor bearing on the crystal, and a plastic material forming a seal over the crystal and conductor for maintaining the crystal and conductor in permanent contact.
20. 2. A hand-carried wireless receiving outfit, comprising a unitary device including a casing, a telephone receiver therein, a detector mounted in the casing and connected across the terminals of the magnet of the telephone receiver, and a variable resistance carried by the casing and connectible in series with the telephone electromagnet and 25 detector.
25. 3. The combination of a casing, a crystal therein, a conductor bearing on the crystal, a plastic material covering the crystal and conductor and maintaining a permanent contact between the two, and means for connecting the crystal and conductor in a wireless 30 circuit.
30. 4. A wireless receiving outfit comprising a casing including a pair of shells, a resistance winding disposed between the shells, variable resistance contacts mounted on the casing and connected with the resistance winding, a binding post with which one end of the resistance winding is connected, a 35 telephone receiver electromagnet arranged in the casing and having one terminal connected with the variable resistance through the said contacts, a binding post to which the other terminal of the electromagnet is 40 connected, a diaphragm arranged within the casing and associated with the electromagnet, and a detector connected across the electromagnet terminals and disposed at the 45 same side of the diaphragm as the electromagnet.
45. 5. A wireless-receiving device comprising
50. a casing, a cup-shaped holder therein, an apertured cap applied to the holder, a diaphragm under the cap, a magnet in the holder and associated with the diaphragm, a detector in the casing and consisting of a crystal and contacting conductor, the terminals of the detector being connected with the terminals of the electromagnet and the detector being disposed at the same side of the diaphragm as the electromagnet, a variable resistance device in the casing and having one terminal connected with the electromagnet, a binding post to which the other terminal of the resistance device is connected, and another binding post to which the other terminal of the electromagnet is connected.
55. 6. A detector comprising a crystal, a conductor bearing thereon, supporting means for the conductor and crystal, and a plastic sealing material covering the crystal and conductor where they contact for maintaining them in permanent engagement.
60. 7. A wireless receiving outfit including a receiver diaphragm, an electromagnet in cooperative relation therewith, a housing for the electromagnet and diaphragm, and a detector rigidly fixed on the housing and connected across the terminals of the electromagnet, whereby a unitary receiver and detector is produced, said detector comprising a crystal, and a conductor having a rigid contact therewith.
65. 8. A wireless receiving outfit comprising a diaphragm, an electromagnet associated therewith, a housing in which the electromagnet and diaphragm are mounted, and a detector carried by the housing and including a crystal connected with one terminal of the magnet and a conductor connected with the other terminal of the electromagnet and bearing on the crystal, and plastic material covering the conductor and crystal for maintaining a permanent contact between them.
70. 9. The combination of a casing, with a detector therein, said detector including a crystal, a conductor bearing on the crystal, and a plastic material maintaining the crystal and conductor in permanent contact.
75. In testimony whereof I have signed my name to this specification in the presence of two subscribing witnesses.

FRANK WALLBERG.
